UNITED STATES PATENT OFFICE.

PAUL S. SMITH, OF NEWBURGH, NEW YORK.

INTERNAL-COMBUSTION ENGINE.

1,073,640.

specification of Letters Patent. Patented Sept. 23, 1913.

Application filed April 22, 1909. Serial No. 491,514.

To all whom it may concern:

Be it known that I, PAUL S. SMITH, a citizen of the United States, residing at Newburgh, county of Orange, and State of New York, have invented a new and useful Improvement in Internal-Combustion Engines, of which the following is a full, clear, and exact description, reference being had to the accompanying drawings, which form 10 a part of this specification.

The object of the invention is to provide an improved type of four cycle internal combustion engine, of the class employed in automobile construction, of superior economy and efficiency.

The invention consists of a motor of this class having certain characteristics of structure and operation, two embodiments of the invention being disclosed in the following 20 description and accompanying drawings.

The advantages of an engine embodying my invention over those commonly employed are hereinafter set forth.

In the drawings: Figure 1 is a vertical 25 sectional view through a pair of cylinders; Fig. 2 is a transverse section on the line 2--2 of Fig. 1; Fig. 3 is a vertical section on the line 3--3 of Fig. 1 with the piston omitted; Fig. 4 is a view, similar to Fig. 3, of another 30 embodiment of the invention; Figs. 5, 6, 7 and 8 are diagrammatic views showing approximately the successive positions of the valve shell in a cycle of its operation.

It will be understood that, while two cylinders A and B are shown in the drawings, it is preferred that four or six cylinders should be employed, which, however, would involve merely the multiplication of those illustrated. The invention, indeed, is capable 40 of embodiment in a single cylinder, and the reference letters are in general applicable to corresponding parts of the two cylinders.

Each cylinder comprises an outer or main 45 casing a, an inner casing b, and a cylinder head c integral with the inner casing b. The two cylinder casings are spaced apart to leave an annular space in which is contained a revoluble valve shell d. In assembling the 50 parts, the shell d is preferably inserted from the top, within the outer cylinder casing a, the former having at its upper end an external flange e adapted to extend into a somewhat deeper recess f formed in the upper 55 edge of the latter. The inner cylinder casing b is then inserted from the top,

its head having a projection g fitting within the recess f and resting upon the flange e of the shell d.

h is the piston reciprocable in the inner 60 cylinder casing b and connected to the crank-shaft i by means of the connecting rod j.

The outer casings a of the two cylinders are preferably integral and have formed 65 therein passages k opening through the walls thereof and communicating with the manifold l connected with the source of supply of the motive fluid. The casings a have also formed therein passages m opening through 70 the walls thereof and communicating with the manifold n connected with the exhaust. The inner cylinder casing d has ports or openings o and p registering respectively with the passages k and m. The ports or 75 openings into the passages k and l and the openings o and p are each long relatively to their width. The shell d is provided with a single port or opening v of the same length as the described openings in the cylinder 80 casings but of substantially greater width, preferably about one-fourth of its circumference.

Secured to and surrounding the lower ends of the shells d of the two casings (which 85 shells extend below the cylinder) are two intermeshing gears q, one of which is driven from a gear r on a countershaft s, this shaft carrying a bevel gear t driven from a bevel gear u on the crank shaft i. The gears are 90 of such relative size that the shells d rotate once to each two revolutions of the crank shaft i.

In the modification shown in Fig. 4, the construction, as shown, is precisely the same, 95 except that the cylinder head c is not prolonged to form an inner cylinder casing, and the piston works within and directly in contact with the shell d.

By reference to Figs. 5, 6, 7 and 8, in connection with the foregoing description, the operation of the engine will be understood. Fig. 5 represents approximately the position of the shell at the beginning of the exhaust stroke, the fluid exhausting through the opening p in the inner cylinder casing b, the opening v in the shell d and the passage m in the outer cylinder casing. These openings remain in communication during the upward stroke of the piston. At the beginning of the downward or suction stroke of the piston, the shell d has reached approxi-

mately the position shown in Fig. 6, and thereafter motive fluid is admitted to the piston chamber through the passage *k*, and openings *v* and *o*. These openings remain in communication until the piston completes its stroke. At the beginning of the next upward or compression stroke of the piston, the shell *d* has reached approximately the position shown in Fig. 7, and during this stroke the shell *d* is moving from the position shown in Fig. 7 to that shown in Fig. 8, and the openings to the inlet and exhaust ports are sealed by the shell. During the next downward or power stroke of the piston, the shell *d* moves from the position shown in Fig. 8 to that shown in Fig. 5, and the openings to the inlet and exhaust ports remain sealed by the shell until just before the piston reaches the end of its stroke, when the exhaust is opened.

It will be understood that the positions of the shells in Figs. 5, 6, 7 and 8, and properly correlated intermediate positions, may also be assumed to represent the several positions assumed at a given time by the shells of the four cylinders of a four-cylinder engine.

It is obvious that the timing of the valve action, that is, the determination of the points in the rotation of the crank at which the inlet and exhaust ports shall be opened and closed, is governed by the width of the ports, their distance from each other and the width of the valve shell port.

Among the advantages possessed by an engine embodying my invention may be enumerated:

1. Relatively greater sharpness of valve action, due to the fact that the valve shell is constantly in motion at a uniform speed, which enables the ports to pass from the closed to the fully open position and vice versa in a smaller arc of crank revolution than is possible with any other construction. This feature enables the inlet port to remain open to its fullest extent during a greater proportion of the suction stroke than is otherwise possible, insuring the introduction of the fullest possible charge of explosive mixture. Similarly, the lead given the exhaust valve in constructions of the usual type may be largely eliminated, without imposing back-pressure on the piston during the exhaust stroke, thereby enabling the more complete utilization of the motive force of the expanding gases during the latter part of the power stroke.

2. More direct and unrestricted course of ingress and egress for gases between the interior of the cylinder and the inlet and exhaust pipes, eliminating to the greatest possible extent friction of gases in the inlet and exhaust passages, thereby obviating wire-drawing effect on the suction stroke and back-pressure on the exhaust stroke. Assuming a given port area, this construction

gives the maximum possible valve efficiency, especially at high motor speeds, since the gases pass from the inlet pipe into the cylinder and from the cylinder into the exhaust pipe in practically a straight line, while in the puppet valve type of construction, they are compelled to make several material changes in direction, particularly in passing the valve heads.

3. Larger ports than are practicable with other types of valve mechanism, while retaining the advantages of relatively sharper action in opening and closing, and unattended by the disadvantages attending the use of large ports in other constructions.

4. Perfect obturation of the combustion chamber during compression and explosion, and the securing of this condition with greater clearance in the working parts than is possible with other constructions, owing to the fact that the obturating surfaces are greater in area than in any other construction.

5. Freedom from loss of compression due to leakage of valves, as occurs in the ordinary construction from erosion, warping, and pitting of the exhaust valve head, seat, and stem.

6. More uniform cooling of cylinder walls, and, indirectly, of the piston, since the rotation of the valve shell tends to transfer any local excess of heat to the entire surface of the cylinder, and conversely tends to compensate any deficiencies or irregularities in cooling effect.

7. Simplification of construction, owing to the elimination of puppet valves and auxiliary constructions.

8. Removal of inlet passages from contiguity with exhaust passages, thereby avoiding excessive heating of the combustible mixture during the suction stroke by radiation from exhaust passages.

9. Relative noiselessness in operation.

10. Complete elimination of reciprocating motion from the valve mechanism.

Having now fully described my invention, what I claim and desire to protect by Letters Patent:—

1. In an internal combustion engine, the combination with a cylinder comprising an external casing and internal casing spaced apart, of an orificed cylindrical valve shell inserted between the two casings of the cylinder, the internal casing having supply and exhaust openings registering respectively with supply and exhaust openings in the external casing, a reciprocable piston within the internal casing, the crank-shaft, and connections between the crank-shaft and valve shell adapted to turn the same to successively connect the piston chamber with the supply and exhaust openings and seal it from both openings.

2. In an internal combustion engine, the

combination with a cylinder having an external casing and an internal casing spaced apart and each provided with supply and exhaust openings, of a rotatable cylindrical valve shell between said casings and adapted to open and close said openings and to connect the openings in the external casing with the openings in the internal casing, a piston within the internal casing, and connections between the crank shaft and the piston and valve adapted to operate the same.

3. In an internal combustion engine, the combination with a cylinder casing having orifices communicating with the supply and exhaust, of a rotatable orificed valve shell within said casing and an orificed casing within the valve, connections between the crank-shaft and valve shell adapted to rotate the same, a piston within the last named casing, and connections between the crank shaft and piston to actuate the latter, said valve adapted in its rotation to open communication from the interior of the cylinder to the supply and exhaust through said orifices.

4. In an internal combustion engine, the combination with the cylinder having supply and exhaust orifices, of a rotatable cylindrical valve shell concentric therewith having a single orifice wider than either of the cylinder orifices and substantially equal in width to the distance between the most adjacent edges of the supply and exhaust orifices and adapted in its rotation to successively communicate therewith, a reciprocable piston within the cylinder and shell, the crank shaft, and connections between the crank-shaft and the valve shell adapted to impart one revolution to the valve shell for two revolutions of the crank shaft.

5. In an internal combustion engine, the combination with the cylinder having supply and exhaust orifices extending longitudinally of the cylinder whose most adjacent edges are approximately ninety degrees

apart, of an orificed valve shell concentric 45 and contacting with the cylinder and having an orifice extending through an arc of approximately ninety degrees and substantially wider than either of the cylinder orifices, a reciprocable piston within the cylinder and shell, the crank-shaft, and connections from the crank-shaft adapted to continuously rotate the shell at one-half the angular speed of the crank-shaft.

6. In an internal combustion engine, the combination with the cylinder having a supply orifice and an exhaust orifice of substantially equal width, of a rotatable cylindrical valve shell concentric therewith having a single orifice adapted in its rotation to successively communicate with said supply and exhaust orifices, said valve orifice on the one hand and each of said cylinder orifices on the other hand being of substantially unequal width and the wider of them extending through an arc of approximately ninety degrees, a reciprocable piston within the cylinder and shell, and connections between the crank shaft and the valve shell adapted to impart one revolution to the valve shell 70 for two revolutions of the crank shaft.

7. In an internal combustion engine, the combination of a cylindrical casing, having lateral suction and exhaust ports, a cylindrical revoluble valve fitting into said casing 75 and adapted to open and close said ports, a piston inside said valve, a crank shaft and a pitman connecting said piston and crank-shaft, and gearing adapted to drive said valve from the crank shaft at a positive 80 ratio.

In testimony of which invention, I have hereunto set my hand, at Newburgh, on this tenth day of April, 1909.

PAUL S. SMITH.
